2 SHEETS—SHEET 2.

UNITED STATES PATENT OFFICE.

PERCY B. BOSWORTH AND FRANK T. LAHEY, OF AKRON, OHIO.

COLLAPSIBLE BOX.

1,177,847.

Specification of Letters Patent.

Patented Apr. 4, 1916.

Application filed January 9, 1914, Serial No. 811,270. Renewed February 23, 1916. Serial No. 80,092.

To all whom it may concern:

Be it known that we, PERCY B. BOSWORTH and FRANK T. LAHEY, citizens of the United States, residing at Akron, in the county of 5 Summit and State of Ohio, have invented new and useful Improvements in Collapsible Boxes, of which the following is a specification.

This invention relates to improvements 10 in metallic shipping packages and embodies a collapsible box of sheet metal comprising a plurality of parts adapted to be assembled to form a box and which can be, if desired, collapsed to occupy a minimum 15 amount of space.

A still further object is to provide a metallic shipping packing of great strength, in which the number of parts are reduced to a minimum which can be readily sealed 20 against unauthorized tampering and which when collapsed will occupy only a fractional portion of the space occupied by the box when set up.

With the foregoing and other objects in 25 view, the invention consists in the novel construction, combination and arrangement of parts constituting the invention to be hereinafter specifically described and illustrated in the accompanying drawings which form 30 a part hereof wherein is shown the preferred embodiment of the invention, but it is to be understood that changes, variations and modifications can be resorted to which come within the scope of the matter herein- 35 after claimed.

In the drawings in which similar reference numerals indicate like parts in the different figures, Figure 1, is a perspective view of a collapsible box embodying this invention; Fig. 2, is a view similar to Fig. 1 with portions of the box broken away to better illustrate the construction thereof; Figs. 3 and 4, are perspective cross sectional views on lines X and Y respectively of Fig. 45 1; Fig. 5, is a perspective view of the box in its collapsible condition; and Fig. 6, is a longitudinal sectional view of the collapsed box shown in Fig. 5.

The box comprises a top 1, a bottom 2, 50 end members 3 and 4, and side members 5 and 6. The top 1 is provided along its side edges with downturned marginal flanges 7 and 8 each of which is provided with L-shaped slots 18 and with end flanges 9 and 55 10, the former preferably unprovided with slots and the latter provided with project-

ing headed studs 11. The flanges 7, 8, 9 and 10 are preferably integrally united at their corners by means such, for instance, as welding to strengthen the entire structure. 60

The lower member or bottom 2 is provided with upwardly-extending marginal flanges 12 and 13 and with end flanges 14 and 15, all preferably united together. The 65 lateral flanges 12 and 13 are provided with L-shaped slots 16 for a purpose to be later described.

The transverse width, that is to say, the width between the flanged portions 12 and 70 13 is less than the distance between the flanges 7 and 8 of the upper member or cover 1 for a purpose to be later described.

The sides 5 and 6 are identical and a description of one is thought to be sufficient 75 for both. Each of the side forming members consists of a sheet of metal slightly less in length than the distance between the flanges 9—10 and the flanges 14—15, to permit longitudinal movement of the side-forming 80 members as hereinafter described. Along the upper edges of the members 5 and 6 a plurality of headed studs 17 are spaced apart distances equal to the distances between the L-shaped slots 18 in the flanged portions 7 85 and 8 of the cover. The shanks of these studs 17 and all the other studs used in this connection are of the proper diameter to be received in the L-shaped slots employed in this device. Adjacent to the left ends of 90 the members 5 and 6 are a series of headed studs 19 and along the opposite ends are a series of studs 20. The lower portions 22 of the members 5 and 6 are inwardly-bent at 95 21 so as to be received within the flanges 12 and 13 of the bottom member 2 and along these indent portions 22 are a series of studs 23 similar to the studs 17, 19 and 20 and properly spaced apart to be received in the L-shaped slots 16 of the flanged portions 12 100 and 13 of the lower member 2. The end member 4 is provided at its sides with in-turned flanges 24 and 25 each of which is provided with a series of L-shaped slots 26 to receive the shank portions of the studs 19 105 and interlock therewith. The upper portion of the member 4 is provided with a portion 27 inwardly-bent at 28.

The end forming member 3 is provided with flanged side portions 29 and 30 provided with L-shaped slots 31 to receive the shank portions of the headed studs 20. The 110

upper portion of this end-forming member 3 is further provided with a plurality of openings 32 through which the heads of the studs 11 freely pass. It is contemplated that 5 all the members described will be made of sheet metal having a uniform thickness, thereby giving to the entire structure when assembled a uniform rigidity.

We claim:—

- 10 1. A collapsible box embodying top and bottom members, both of which are provided with lateral and end flanges at right angles thereto, the lateral flanges provided with L-shaped slots, side members provided with studs positioned along their edges and arranged in lapping engagement with the inner faces of the lateral flanges of the top and bottom members and with the studs interlocked in the L-shaped slots thereof, the lower portions of said side members having 40 indent portions to seat within the bottom member, end-forming members having side flanges provided with L-shaped slots adapted to interlock with the studs on said side members, the upper end of one of said members being indent and adapted to lap the inner face of the end flange of the cover and the opposite end-forming member adapted to lap the outer faces of the flanges of both bottom and cover, and means to prevent 45 shifting movement of the cover.
- 15 2. A collapsible box embodying top and bottom members, both of which are provided with lateral and end flanges at right angles thereto, the lateral flanges provided with L-shaped slots, side members provided with studs positioned along their edges and arranged in lapping engagement with the inner faces of the lateral flanges of the top and bottom members and with the studs interlocked with the L-shaped slots thereof, end-forming members having side flanges provided with L-shaped slots adapted to interlock with the studs on said side members, the upper end of one of said end members being indent and adapted to lap the inner 50 face of the one end flange of the cover and the opposite end-forming member adapted to lap the outer faces of the flanges of both bottom and cover, and means to prevent shifting movement of the cover.
- 20 3. A collapsible box embodying top and bottom members, both of which are provided with lateral and end flanges at right angles thereto, the lateral flanges provided with L-shaped slots, side members provided with studs positioned along their edges and arranged in lapping engagement with the inner faces of the lateral flanges of the top and bottom members and with the studs interlocked with the L-shaped slots thereof, end-forming members having side flanges provided with L-shaped slots adapted to interlock with the studs on said side members, the upper end of one of said end members being indent and adapted to lap the inner 55 face of the one end flange of the cover and the opposite end-forming member adapted to lap the outer faces of the flanges of both bottom and cover, and means to prevent shifting movement of the cover.
- 25 4. A collapsible box embodying top and bottom members, both of which are provided with lateral and end flanges at right angles thereto, the lateral flanges provided with L-shaped slots, side members provided with studs positioned along their edges and arranged in lapping engagement with the inner faces of the lateral flanges of the top and bottom members and with the studs interlocked with the L-shaped slots thereof, end-forming members having side flanges provided with L-shaped slots adapted to interlock with the studs on said side members, the upper end of one of said end members being indent and adapted to lap the inner 60 face of the one end flange of the cover and the opposite end-forming member adapted to lap the outer faces of the flanges of both bottom and cover, and means to prevent shifting movement of the cover.
- 30 5. A collapsible box embodying top and bottom members, both of which are provided with lateral and end flanges at right angles thereto, the lateral flanges provided with L-shaped slots, side members provided with studs positioned along their edges and arranged in lapping engagement with the inner faces of the lateral flanges of the top and bottom members and with the studs interlocked with the L-shaped slots thereof, end-forming members having side flanges provided with L-shaped slots adapted to interlock with the studs on said side members, the upper end of one of said end members being indent and adapted to lap the inner 65 face of the one end flange of the cover and the opposite end-forming member adapted to lap the outer faces of the flanges of both bottom and cover, and means to prevent shifting movement of the cover.

bottom members both of which are provided with lateral and end flanges at right angles thereto, the lateral flanges provided with L-shaped slots, side members provided with studs positioned along their edges and arranged in lapping engagement with the inner faces of the lateral flanges of the top and bottom members and with the studs interlocked in the L-shaped slots thereof, the lower portions of said side members having 40 indent portions to seat within the bottom member, end-forming members having side flanges provided with L-shaped slots adapted to interlock with the studs on said side members, the upper end of one of said members being indent and adapted to lap the inner face of the end flange of the cover and the opposite end-forming member adapted to lap the outer faces of the flanges of both bottom and cover, and means to prevent 45 shifting movement of the cover.

In testimony whereof we have hereunto set our hands in presence of two subscribing witnesses.

PERCY B. BOSWORTH.
FRANK T. LAHEY.
